UNITED STATES PATENT OFFICE.

CHARLES H. SHULTZ, OF ST. JOSEPH, MISSOURI.

VAPOR-BURNER.

SPECIFICATION forming part of Letters Patent No. 400,498, dated April 2, 1889.

Application filed May 17, 1887. Renewed February 23, 1889. Serial No. 300,995. (No model.)

To all whom it may concern:

Be it known that I, CHARLES H. SHULTZ, a citizen of the United States, residing at St. Joseph, in the county of Buchanan and State 5 of Missouri, have invented a new and useful Improvement in Vapor-Burners for Gas-Stoves, of which the following is a specification.

My invention relates to an improvement in 10 vapor-burners; and it consists in the peculiar construction and arrangement of the devices, as will be more fully set forth hereinafter, and particularly pointed out in the claims.

In the drawings, Figure 1 is a vertical sectional view of a vapor-burner embodying my 15 improvements. Fig. 2 is a top plan view of the same. Fig. 3 is another form of the packing device for the needle-valve.

A represents a hollow annular casting, 20 which constitutes the generating-chamber. This chamber is preferably made annular in form and surrounds a central open space, B, which is open from top to bottom throughout the height of the chamber. From one side 25 of the chamber A projects an offset, C, which forms the cap of and is connected to the upper end of the usual stand-pipe, D, by a screw-coupling, as shown. From the opposite side of the generating-chamber extends a vapor- 30 pipe, E, to the lower end of which is attached a horizontal sleeve, F, which has its closed apertured extremity projected toward the stand-pipe. In this sleeve is located the needle-valve G. The outer end of the horizontal 35 sleeve F is provided with screw-threads, as shown in Fig. 1, and the closed inner end of the said sleeve has a conical central aperture, R.

S represents a packing-gland, which is 40 cylindrical in shape, and is provided with interior screw-threads adapted to fit the threads on the outer end of the sleeve F.

G represents the needle-valve, which fits in the sleeve F, and is provided at its inner end 45 with the usual conical needle-point extending through the aperture R. The outer portion of the needle-valve is provided with screw-threads U, which engage a threaded opening in the bottom of the gland S.

50 V represents packing material, which is arranged in the packing-gland on the outer end

of the sleeve F and around the needle-valve G. By turning the gland so as to cause it to be screwed on the sleeve F the packing material may be compressed to such a degree as 55 to absolutely prevent the escape of vapor from the outer end of the sleeve F.

W represents a handle, which is secured to the lower depending end of the needle-valve by means of a set-screw, X.

H represents a combined mixing-chamber and burner-head, which has its upper end part way inserted in the space and arranged concentrically in the said space. The lower end of the mixing-chamber and burner-head 65 is provided with an integral tube, I, which is open at its outer end, and is projected toward the inner end of the sleeve F. This mixing-chamber and burner-head may be supported by an arm, K, projecting from the 70 stand-pipe, as shown in the accompanying drawings; or it may be supported in any other suitable manner. The upper end of the mixing-chamber and burner-head is provided with a number of horizontal radial openings, 75 L, some of which are slightly above the lower side of the generating-chamber and the others are below the same.

M represents a drip or oil cup, which forms an annular flange-extension of the cap of the 80 mixing-chamber and burner-head. This cap is secured in position by means of the vertical clamping-bolt N, as shown in Fig. 1.

The operation of my invention is as follows: In starting the burner in operation a small 85 quantity of oil is placed in the cup N and is ignited, thereby causing the generating-chamber, which is directly over the oil-cup, to become thoroughly heated. When the oil is permitted to flow from the reservoir (not 90 shown) through the stand-pipe D into the generating-chamber, it becomes vaporized therein, and the vapor passes through the pipe E and the sleeve F and is directed by the aperture in the said sleeve into the burner-head through the open tube I thereof. As 95 the said vapor enters the burner-head it sucks the air into the burner-head, which air mingles with the vapor and renders the latter combustible. As the oxygenized vapor 100 passes outward from the burner in small jets through the openings L, it burns in a

flame, which strikes against the lower and inner sides of the annular generating-chamber, and thus keeps the said generator so hot that it is caused to generate vapor as fast as it is consumed by the burner. Exterior air is drawn upward by the flame and heat through the space B and around the upper end of the burner H in sufficient quantities to insure perfect combustion of the vapor.

Particular stress is laid on the construction of the burner-head and commingling-chamber with the series of perforations in the sides above and below the lower side of the generator, whereby the jets of flame are projected laterally against the bottom and lower sides of the generator-chamber, causing the latter to be thoroughly heated to effect the vaporization of the oil. By having the jet-openings in the sides instead of at the top the flame is caused to strike the bottom of the generator-chamber and cannot escape without touching the chamber. Again, the burner is arranged out of contact with the lower side of the generator, to leave a space through which air can escape through the space B of the generator to feed combustion.

The construction of packing shown in Figs. 1 and 3 is claimed in my application, Serial No. 238,348, filed May 16, 1887. In Fig. 3 I show an improved form of packing. The gland S screws upon the tube F in the manner shown in Fig. 1; but in the present instance I employ a cap, W², held rigid on the valve-stem by a set-screw, X², and this cap, W² screws over the threaded outer end of the gland S. By this arrangement the cap W² is caused to screw or unscrew over the threaded outer end of the gland by the movement of the valve G. The object of this construction is to dispense with the necessity of threading the valve, as in the construction shown in Fig. 1, and at the same time secure the proper movement for the valve. By the turning of the valve the box W² works over the outer end of the gland to give the proper movement to the valve. By this means the turning of the valve G effects the packing thereof, and leaking of the gas is entirely overcome. Should any gas escape from the valve, it will be arrested by the packing-gland. No stuffing-boxes are required to be used in this packing device, and this is a point gained, as every one familiar with this art will admit.

Particular stress is laid on the arrangement of the burner within the air-space B of the generating-chamber, whereby the said air-space is not closed by the burner, but a space is left around the burner and between it and the generating-chamber to allow a free upward draft of air for the purpose of assisting combustion.

It has been found in practice that unless the flame's jets are supplied with a sufficient quantity of air the jets will be of a yellowish color and cause smoking, with an offensive odor. By my construction the flame-jets are supplied with air in such quantities as to insure perfect combustion, causing the flame-jets to be of a purplish color, devoid of smoke or odor.

I am not aware that any vapor-burner having a central opening or air-space, B, has ever been constructed with the burner located in the same but not closing the said air-space, so that a free upward current of air around the burner is insured at all times.

Having thus described my invention, I claim—

1. In a vapor-burner, the generating-chamber A, surrounding a central space, B, which is entirely open both at the top and bottom, combined with the burner-head arranged below the generating-chamber and having its upper end inserted part way into the open space B, the top of the burner being closed and imperforate, and two or more series of jet-openings, L, in the sides of the burner-head, one series being above the other, so that the openings L are both above and below the bottom of the generating-chamber, as set forth.

2. In a vapor-burner, the generating-chamber A, surrounding a central space, B, which is open at the top and bottom, and the combined mixing-chamber and burner H, arranged below the generating-chamber, the burner-head being inserted into the space B, and having a removable cap provided with a flanged extension, which forms an oil-cup, M, the top of the cap being imperforate, and the perforations L in the sides of said cap, as set forth.

3. In a vapor-burner, the generating-chamber A, surrounding a central space, B, which is open at the top and bottom, and the vapor-pipe E, extending from the chamber, in combination with the combined mixing-chamber and burner H, made separate from the generating-chamber and having its upper end inserted part way into the space B and its lower end formed with an integral tube, I, which is turned to one side toward the pipe E, and the needle-valve at the lower end of pipe E, adjacent to the end of tube I, and the jet-openings L in the sides of the burner, said openings being both above and below the bottom of the generating-chamber, the top of the burner being imperforate, as set forth.

In testimony that I claim the foregoing as my own I have hereto affixed my signature in presence of two witnesses.

CHARLES H. SHULTZ.
